INTERNAL COMBUSTION ENGINE

Gage C. McDermett, Wichita Falls, Tex.

Application June 25, 1937, Serial No. 150,381

3 Claims. (Cl. 123—59)

This invention relates to internal combustion engines of the type having a rotary cylindrical valve in the head thereof and extending over the tops of the engine cylinders.

The primary object of the present invention is to provide a rotary valve mechanism of the above kind which is of generally improved construction, easy and economical to construct and maintain in efficient operating condition, and otherwise adapted to meet with all of the requirements for a successful commercial use.

A more particular object of the present invention is to provide an improved rotary valve mechanism of the above kind embodying simple and efficient means for maintaining a fluid tight relation between certain portions of the rotary valve and the wall of the valve chamber so as to effectively prevent leakage therebetween from one cylinder to another, or from the inlet to the discharge port of each cylinder or vice versa.

Another important object of the present invention is to provide for the efficient circulation of water through the rotary valve to cool the latter.

Other objects of the present invention will become apparent from the following description when considered in connection with the accompanying drawings, and the invention consists in the novel form, combination and arrangement of parts hereinafter more fully described, shown in said accompanying drawings and claimed.

In the drawings:

Figure 1 is a substantially central longitudinal sectional view through the head and the upper portion of the cylinder block of a multi-cylinder engine equipped with a rotary valve mechanism constructed in accordance with the present invention.

Figure 2 is a view partly in vertical section on line 2—2 of Figure 1 and partly in front elevation, of the construction shown in Figure 1.

Figure 3 is a vertical section on line 3—3 of Figure 1.

Figure 4 is a view on the same line as Figure 3 but looking toward the left of Figure 1 with the head and block in rear elevation.

Figure 5 is an enlarged vertical section on the plane of line 5—5 of Figure 1, but with the valve turned to a different position.

Figure 6 is a fragmentary longitudinal section on line 6—6 of Figure 5.

Figure 7 is a similar view on line 7—7 of Figure 5.

Figure 8 is a perspective view of one of the packing strips forming part of the valve bear-

ing employed in connection with each cylinder; and

Figures 9 to 16 inclusive are diagrammatic views illustrating various positions of the valve with respect to each cylinder during the operation of the engine.

Referring in detail to the drawings, the engine illustrated comprises a cylinder block 5 having four cylinders 6 in which are pistons 7, a head being secured upon the block 5 including a lower section 8 bolted to the block as at 9 and an upper section 10 bolted to the lower section as at 11. The head sections 8 and 10 are formed with mating semi-cylindrical recesses which form a cylindrical valve chamber in which is rotatably fitted a cylindrical valve 12 having diametric ports 13 extending therethrough, one for each cylinder. The head sections 8 and 10 have aligned diagonal intake ports 14 and 15 respectively, as well as oppositely inclined diagonal and aligned exhaust ports 16 and 17 respectively, for each cylinder. Thus, each port 13 of the valve is adapted to establish communication between intake ports 14 and 15 to connect the associated cylinder with an intake manifold, and to establish communication between the exhaust ports 16 and 17 to connect said cylinder to an exhaust manifold, in certain positions during the revolution of the valve. These intake and exhaust manifolds are respectively indicated at 18 and 19 and form portions of a single unit or casting which also includes an intermediate web 20 connecting said manifold. The inner walls of manifolds 18 and 19 below the web 20 are respectively provided with outlet and inlet openings 21 and 22 respectively adapted to register with the intake port 15 and exhaust port 17 of the upper head section 10, the web 20 resting upon the upper head section 10 between the ports 15 and 17 and being bolted to said head section 10 as at 23. Thus, the manifold unit is of a saddle type construction, and the wall portions of the manifolds, as well as the surfaces of the upper head section 10 with which they contact are preferably inclined in downwardly diverging relation so that the manifold unit has a self-centering seating engagement upon the head section 10. A suitable gasket 24 may be employed between the manifold unit and the head section 10 to provide a gas-tight joint therebetween, and similar gaskets, not shown, may of course be employed between the meeting faces of the head section and between the block 5 and the lower head section 8.

The block 5 is of the usual bevel-wall construction so as to provide water jackets 25 about

the cylinders which communicate with each other, and the lower and upper head sections 8 and 10 are also of hollow construction to permit circulation of water therethrough for cooling purposes in a well known manner. The lower head section receives the cooling water from the jackets 25 of the cylinders through the top of said jackets 25 in the usual manner, and similar communication is provided between the interiors of the head sections 8 and 10. The valve 12 is of hollow construction with the ports 13 afforded by tubular members extending diametrically through said valve. At the rear end of the engine, the lower head section 8 is provided with water outlet openings 26, and bolted as at 27 to this end of head section 8 is a cap member 28 of hollow construction having water inlet openings 29 adapted to register with the openings 26 so as to permit passage of the cooling water from the head section 8 into the cap member 28. The cap member 28 is provided at its inner side with a packing gland 30 through which projects the adjacent end of valve 12 as shown clearly in Figure 1. This provides a water-tight joint between the cap member 28 and the adjacent end of valve 12, and the cooling water passes from cap member 28 into the interior of valve 12 as indicated by the arrows *a* in Figure 1. The adjacent end of valve 12 is flanged as at 31 so as to afford a longitudinal thrust bearing for the bearing in said cap member 28. At the opposite or front end of the head, another cap member 32 is bolted to the lower head section 8 as at 33 and has at its inner side a packing gland 34 through which the adjacent or front end of valve 12 projects. The packing gland 34 forms a water-tight joint between the cap member 32 and the adjacent end of valve 12, the latter being formed on its outer side with a pump casing 35 having a removable front wall 36. As shown clearly in Figure 1, the front end of valve 12 opens into the chamber of pump casing 35, and said pump casing 35 has a tangential outlet 36 adapted to be connected in the usual way with a heat dissipating radiator wherein the heat is dissipated from the cooling water before it is returned again to the water jackets of the cylinders 6. Provision is thus made for efficient circulation of cooling water through the valve, as well as the head sections, thereby preventing undue heating of these parts. Secured to the front end of valve 12 and projecting forwardly therefrom coaxial therewith is a shaft 38 on which is keyed an impeller 39 arranged within the pump casing 35. The shaft 36 is connected to the valve 12 by radial arms 40 so as to permit passage of the cooling water from valve 12 into pump casing 35. The shaft 38 projects forwardly through a packing gland 41 provided on the removable outer wall 36 of pump casing 35, and the projecting forward terminal of shaft 38 may have a sprocket gear 42 secured thereon to facilitate transmission of power from the crank shaft of the engine to the rotary valve for rotatably driving the latter at the proper speed. At each cylinder, the lower head section 8 is provided with a suitable spark plug recess 43 aligned with a threaded opening 44 for removable reception of a spark plug 45, as shown clearly in Figure 5. Also, the manifold 18 may be provided intermediate its ends and on the outer side thereof with an inlet 46 for connection with the outlet of a carburetor, the manifold 19 having an outlet opening 47 at the rear end thereof for communication with the usual exhaust pipe.

At the opposite sides of each port 13, the valve 12 is provided with annular external ribs 48 adapted to be received in corresponding but slightly wider annular grooves 49 formed in the wall of the valve chamber. Cylindrical bearing sleeves for the ported portions of the valve 12 between its ribs 48, are fitted in the valve chamber, one between each pair of adjacent grooves 49, and each bearing sleeve consists of a pair of semi-cylindrical sections 50 and 51 having end flanges 52 and 53 arranged to engage in the adjacent grooves 49 and cooperate with the adjacent ribs 48 to provide longitudinal compression seals. In surrounding relation to each of the ports 14 and 16, the wall of the valve chamber has inwardly projecting bevelled ribs or lips 54 as shown more clearly in Figures 5 and 7, and these ribs or lips engage correspondingly bevelled side and end walls of exhaust and intake openings provided at 55 and 56 in the lower sections 50 of the bearing sleeve. This arrangement provides fluid-tight joints for preventing leakage between the adjacent parts from port 15 to adjacent port 16 or vice versa, or from the ports 14 and 16 of one cylinder to those of an adjacent cylinder. Also, this arrangement provides for retaining the bearing sleeve against rotation with the valve. In addition to this primary sealing means, packing bars 57 are provided in the lower bearing sleeve sections 50 at the outer sides of ports 14 and 15, said packing bars being pressed by leaf springs 58 into engagement with the periphery of the valve 12. The packing bars 57 are preferably provided with recesses 59 in the outer sides thereof to accommodate the springs 58, the bars 57 being arranged in suitable openings provided in the lower bearing sleeve sections 50. As indicated at 60 (Figure 6) the walls of these openings in sections 50, as well as the ends of the bars 57 are correspondingly bevelled so that the bars 57 will readily center themselves against said openings. The springs 58 may be substantially flat although reacting against the wall of the valve chamber to press the bars 57 inwardly and maintain them in tight engagement with the cylindrical surface of the rotary valve. These packing bars provide an additional and more efficient means for preventing leakage from port 16 to port 15 or from port 14 to port 17, with respect to each cylinder.

The valve may be provided with any suitable lubricating means, although the oil is preferably led to the grooves 49 through feed tubes 61 carried by the upper head section 10 as generally indicated in Figure 5.

The operation of the valve will be apparent from Figures 9 to 16 inclusive. In Figure 9 the valve 12 is positioned with a port 13 about to open communication between the associated parts 14 and 15 of a cylinder, communication having been cut off between the associated ports 16 and 17. At this time, the piston in the associated cylinder is at the top of its stroke and ready to descend for drawing in an explosive charge. Further travel of the valve brings it to the position of Figure 10 wherein the intake is completely opened with the piston midway of its suction stroke. When the piston reaches the end of its suction stroke, the valve reaches the position of Figure 11 so as to close communication between the ports 14 and 15, the ports 16 and 17 being still out of communication. At this time, the piston is ready to ascend for compressing the charge just taken in to the cylinder. When the valve turns further to the position of Figure 12,

the piston is midway its compression stroke, and when the valve reaches the position of Figure 13, the piston has completed its compression stroke and the charge is fired. This drives the piston 5 downwardly or outwardly and when the piston is midway its power stroke, the valve is in the position of Figure 14. When the piston reaches the end of its power stroke and is ready to ascend, the valve reaches the position of Figure 15 where- 10 in the same is about to establish communication between exhaust ports 16 and 17. This communication is fully opened as shown in Figure 16 when the piston reaches a point midway its exhaust stroke as shown in Figure 16, the valve 15 finally coming back to the position of Figure 9 at the end of the exhaust stroke of the piston when the piston is again ready to descend on its intake stroke. The same performance takes place at the proper time with respect to each 20 cylinder, as will be readily understood by those familiar with the operation of a four-cycle engine.

From the foregoing description, it will be seen that I have provided a construction of valve 25 mechanism which is fully adapted to meet with all of the requirements for a successful commercial use and which is efficient in carrying out the stated objects of the invention. The parts are simple and may be readily and economically produced and assembled or taken apart for renewal or repair. Also, efficient operation is insured with a minimum amount of care or attention. While I have illustrated a very specific embodiment of the invention, it is apparent that the same is 30 susceptible of many modifications and changes such as fairly fall within the spirit and scope of the invention as claimed. It will be noted that the valve is adapted to be rotated in ratio of 1 to 4 with the engine crank shaft by suitable driving mechanism, and that the ports in both the 35

valve and valve casing are in ratio of 1 to 16 of the circumference of the valve.

What I claim as new is:

1. In an engine, the combination of a valve casing having inlet and exhaust ports and provided with ribs in surrounding relation to said ports, a rotary cylindrical valve mounted in said casing and having a port for cooperating with said inlet and exhaust ports, a bearing sleeve surrounding said valve and having ports registered with said inlet and exhaust ports, said rib and the walls of the ports of said bearing sleeve having contacting bevelled surfaces. 5 10 15

2. In an engine, the combination of a valve casing having inlet and exhaust ports and provided with annular circumferential grooves at opposite sides of said ports, a rotary cylindrical valve mounted therein and having a port for cooperating therewith, said valve further having annular external ribs engaged in said annular 20 25 grooves, and bearing sleeves encircling the valve and provided with end flanges engaging in said annular grooves and cooperating with the annular ribs of the valve for providing longitudinal compression seals.

3. In an engine, a valve casing having a cylindrical valve chamber and inlet and exhaust ports at opposite sides of said chamber, a rotary cylindrical valve mounted in said casing and having a port for cooperating with said inlet and exhaust ports, a bearing sleeve surrounding said valve and provided with inlet and exhaust ports, said valve casing having ribs surrounding the inlet and exhaust ports at the inner side of the valve chamber and engaging the inlet and exhaust ports of the bearing sleeve to afford sealing means and to restrain the bearing sleeve against rotation with the valve. 30 35

GAGE C. McDERMETT. 40
